COMBINED TYPEWRITING AND COMPUTING
MACHINE

Henry L. Pitman, Westfield, N. J., assignor, by
mesne assignments, to Underwood Elliott Fisher
Company, New York, N. Y., a corporation of
Delaware

Application May 17, 1932, Serial No. 611,838.

36 Claims. (Cl. 235—60)

This invention relates to combined typewriting and computing machines in which indexing mechanism is operated by the numeral-type-keys to set digit-pins in one or more sets of bars for driving the registers. Into said registers the indexed amount may be accumulated by a cycling mechanism after said amount is typed on the work-sheet.

This application discloses a novel elimination or throw-off key mechanism for selectively suppressing one or more registers during a cycling operation. Other improvements relate to novel organizations of the machine conducing to efficiency of operation and economy of manufacture.

The Underwood bookkeeping machine has devices whereby the letter-feeding carriage as it enters a computing zone selects the sets of pin-bars in which an amount is to be indexed, the arrangement being such that, in different computing zones, different individual registers are called into action. The individual pin-bars of whatever set is selected are indexed in denominational order as the carriage advances step by step in a computing zone in response to actuation of the numeral-type-keys, it being understood that indexing may be effected simultaneously in more than one set of pin-bars in any zone, or in different individual sets of pin-bars in different zones. Denomination-selecting trains extend from different sets of pin-bars to the carriage which carries tappets to actuate said trains. Other trains, each individual to a corresponding set of pin-bars, also extend to the carriage for enabling the latter to select by means of other tappets the one or more sets of pin-bars to be indexed.

As set forth in my co-pending application, Serial No. 324,353, filed December 7, 1928 (now Patent No. 1,927,951, dated September 26, 1933), the pin-bars have drive-racks and sets of idlers permanently in mesh therewith, the computing pinions being normally out of mesh with both racks and idlers. When said pinions are in mesh with the racks they are rotated in one direction, as for addition. When they are meshed with the idlers, they are rotated reversely, as for subtraction, each set of computing pinions being mounted in a shiftable frame, so that said pinions may be meshed either with the racks or the idlers.

As set forth in my co-pending application, Serial No. 472,610, filed August 2, 1930, a single or trunk set of denominational trains extending from the carriage is ramified by means of a

series of denominational cross-shafts and distributing arms thereon to serve the several sets of pin-bars. Each set of distributing arms has shiftable couplers normally displaced from the pin-bars, but shiftable as a group into effective position, so that the seriatim rocking of said shafts may advance corresponding pin-bars to pin-setting position under a set of pin-setting linkages extending across all the sets of pin-bars, and thus being capable of serving any set. It is by the shifting of any set of couplers into effective position that a corresponding set of pin-bars is selected for indexing. From each set of couplers there extends, therefore, to the carriage, a train which is actuated by a tappet on said carriage.

As set forth in my co-pending application, Serial No. 607,275, filed April 25, 1932 (now Patent No. 2,091,717, dated August 31, 1937), there are provided state-controlling means individual to each register, the function of which is to predetermine, upon proper setting thereof, whether the computing pinions are to mesh with the racks for addition, or whether they are to mesh with the idlers for subtraction, during the cycling operation, it being understood that in said cycling operation, the indexed amount is run into the selected registers.

A feature of the present improvements is directed to individual throw-off key mechanisms for the several registers. According to the usual practice, an elimination key is used to silence a register, so that an amount indexed in its pin-bars will not be run into said register. For example, if it is desired to take the total indicated in one register, the indicated total is typed on the work-sheet and corresponding index-pins are set in the pin-bars of said register. The register is then conditioned for subtraction and the machine is cycled, causing said register, from which the total was transcribed, to be cleared. The set-up of the carriage-tappets, however, may be such that the amount corresponding to said total is also set up in some of the other pin-bars, in which case other registers would erroneously register said amount during the cycle initiated to clear the one register. To obviate this, it has been the practice heretofore to press the elimination key for each of the registers except the one from which the total was to be transcribed, said elimination key heretofore actuating mechanism to restore the digit-pins of the pin-bars for the registers whose disuse was desired during the total-transcribing operation. Such being the function of the elimina-

tion key heretofore, that is, to reset index-pins, it was necessary that said key should be operated after the amount was typed. Sometimes an operative would inadvertently operate the elimination key or keys before the amount was typed and then proceed with the typing. It is evident that premature operation of the elimination key would not eliminate the unwanted settings of the pins, and consequently amounts would be 10 wrongly registered in some of the registers.

To overcome this difficulty, the novel throw-off-key mechanism for each of the registers is arranged so that it may be operated without regard to prior operation of the numeral-keys. For 15 example, if computation has been effected in one zone by typing an amount and accumulating said amount in one or more registers, and it is then desired to transcribe a total from one of the registers, the novel throw-off-key mechanism may be 20 operated at any time between the completion of said computation and the cycling of the mechanism for clearing the register from which the total is to be transcribed. The operative may tabulate the carriage to the position in which 25 it will be when the total is transcribed, and press the throw-off key after transcribing said total; or she may operate said key before the total is transcribed, or she may even operate said key before tabulating said carriage. In any case, the 30 novel throw-off-key mechanism will be effective to silence its corresponding register.

To this end, the throw-off-key mechanism may interact with the state-controlling means of the corresponding register, said state-controlling 35 means assuming different positions, depending on whether the register is to be conditioned for addition or subtraction. Means are provided whereby operation of the throw-off key restores the state-controlling means to neutral position and 40 latches said means in said position where they are held until the computing mechanism is cycled for clearing the register from which the total is transcribed. Upon such cycling of the computing mechanism, it is contrived to automatically release 45 the previously set throw-off-key mechanism, and the state-controlling means thereupon automatically becomes free again to assume any subsequent position determined by the carriage, whether it be in the same zone in which the total was transcribed or in another zone. It will 50 be understood that the throw-off-key mechanism may be used on other occasions than the transcription of a total, as, for example, when an amount is to be accumulated in a less number 55 of registers than the number of registers called into action by the carriage.

Another feature of improvement relates to the arrangement of the keys of the typewriter-keyboard. In the improved Underwood typewriter 60 with which the computing mechanism is combined, a row or bank of denominational tabulating keys is arranged behind the rearmost row of the usual four-bank typewriter-keyboard. For joint use with the usual computing mechanism upon 65 which the typewriting machine is superposed, there are sometimes provided extra registers directly operated by the numeral-keys and arranged to move with the typewriter-carriage, as set forth, for example, in the Kurowski Patent 70 1,835,165, dated December 8, 1931. Such carriage-borne registers and controlling mechanism therefor overhang the keyboard, making it inconvenient for the operative to give a directly 75 downward thrust to the keys, particularly the tabulating keys and the keys of the rearmost

bank of the typing keyboard. To overcome this difficulty, the keys themselves are pitched forwardly at graded angles, that is, the keys of the rearmost or tabulating row are pitched the most, the keys of the next row to the front of the machine, which is the rearmost of the regular keyboard, being pitched at a less angle. The key-tops of the keyboard as a whole, therefore, present a gradually increasing upward slope which is conducive to ease of key-operation, and is of 10 benefit even though the typewriter does not have the overhanging carriage-borne registers and associated controlling mechanism. 5

Another feature of improvement relates to the arrangement of the means whereby the typewriter is supported above the computing mechanism. Heretofore the denominational tabulating key-levers extending from the front to the rear of the typewriter were arranged below the typewriter-base, the tabulating keys being at the 20 front of the typewriter-keyboard and outside of the typewriter-framework. With the tabulating keys arranged behind and above the regular keyboard, as aforementioned, it is feasible to lower the entire typewriter with respect to the computing mechanism. The computing-mechanism framework, therefore, including the casing, has formed in the top of said casing a depression, channel, or opening into which the typewriter is set, the casing rising at the sides of the typewriter 30 sufficiently to afford room for certain controlling keys of the computing mechanism. The novel arrangement of said casing is conducive to neatness of appearance and compactness. 25

Another feature of improvement relates to the pin-setting mechanism. In said mechanism, there is provided for each numeral-key a rock-shaft to operate a parallel motion linkage extending across all the pin-bars. Each rock-shaft has an arm for engagement by its numeral-key 40 and an additional arm rising upwardly from said shaft for thrusting a horizontal transverse bar endwise. An associated bar is depressed edge-wise for depressing the index-pins, the two bars being linked at their ends by bell-crank which 45 translate the endwise movement of the upper bar into edgewise downward movement of the lower bar. It is desirable to keep these bars light to minimize inertia, thereby conducing to easy key-touch. As has been stated, said bars span the 50 several groups of register-pin bars, and, where many of said pin-bar groups are employed, there is a correspondingly wide span between the points at which said bars are supported by the bell-crank, and there is apt to be considerable deflection in the downwardly edgewise moving bar as it attempts to set a pin in any middle group of pin-bars. To avoid this difficulty, the key-controlled rock-shaft has an additional arm, which, when said rock-shaft is actuated bears on and 55 therefore braces the downwardly moving pin-setting bar and substantially minimizes upward deflection thereof as it sets a pin. The transverse span of the group of key-operated rock-shafts is no greater than the span of the numeral-key row, 60 and, in the case of a multiple-register machine, the span or length of the pin-setting bars extends considerably beyond either side of the group of rock-shafts. Thus, by means of the aforesaid addition rock-shaft arm, bearing on the descending pin-setting bar, there is afforded an intermediate support against deflection between the bell-crank supported ends of said pin-setting bars. 65

The pin-bars are advanced seriatim by the car- 70 75

riage to bring their pins under the transverse pin-setting bars, each pin-bar after having been so advanced being restored to its fully retracted position by a spring-device, as the carriage steps ahead and causes the advance of the next pin-bar to pin-setting position. For proper meshing of the computing pinions with the pin-bar racks or with the idlers, the teeth of said racks must be in transverse alignment. If, for any reason, 10 as for example, in speedy operation of the machine, the pin-bar is not fully restored by said spring-device, the computing pinions, which are themselves in transverse tooth-alignment, will not mesh properly and may jam or they may register an amount incorrectly.

A further feature of improvement is the provision of means for positively aligning the pin-bars transversely before the computing pinions are shifted into mesh. A transverse aligning member engaging notches in the pin-bars is provided, and it is contrived to operate said member positively to insure alignment of all the pin-bars, and then to withdraw said aligning member from the notches of the several pin-bars before 25 the latter are advanced to rotate the computing pinions.

The aligning member is in the form of a straight elongate blade which is positioned on edge and spans all the pin-bars. Normally said blade has its lower edge within the aforesaid notches of the several pin-bars, said edge being advanced from the rear edges of said notches, so that the pin-bars may be advanced slightly to pin-setting position. The blade is swingably 30 mounted so that its lower edge may be swung backward, said edge then abutting the rear edges of said notches and having then effected the retraction of any pin-bar that was out of alignment. After the alignment of the pin-bars has been assured by swinging the blade, it is contrived to raise the latter to withdraw it from the notches, so that the pin-bars may advance for rotating 35 the computing pinions. Swinging and withdrawal of the blade are effected by the cycling mechanism, the swinging taking place at the beginning of a cycle, just before the computing pinions are meshed. The withdrawal of the blade may be done concomitantly with the pinion-meshing operation, and it will be understood that this 40 meshing is completed before the pin-bars advance. At the end of the cycle the aligning blade is permitted to drop into its normal position again within the aligning notches of the pin-bars, which will have been restored to normal position 45 at said end of the cycle.

The cycling mechanism or general operator has a reciprocating cross-bar for engaging the depressed pins of the pin-bars to advance the latter for rotating the computing pinions. Said 50 pin-bars also have lugs engageable by said cross-bar to effect restoration of the pin-bars. The engagement of the reciprocating cross-bar with the depressed pins in the forward stroke or with the lugs in the rearward stroke is noisy. It is contrived to minimize the noise by providing the 55 cross-bar with cushioning devices, in the form of coiled springs, that is, closely-wound helices, secured to the front and rear faces of said cross-bar, to span transversely the different sets of pin-bars. The springs are backed up by resilient 60 padding and may be retained within grooves in said cross-bar faces. A rod extends through the spring and projects beyond either end thereof, so that it may be secured by screws. As previously 65 stated, the pin-bars are restored to a fully re-

tracted position from which they are advanced seriatim for pin-setting, and are also retracted seriatim by the aforesaid spring-devices against an abutment. Said abutment may also be provided with a cushioning device formed of a coiled 5 spring, a resilient backing and an internal retaining rod.

Other features and advantages will hereinafter appear.

In the accompanying drawings,

Figure 1 is a skeleton perspective view of a register and a state-determining controller therefor, and illustrates the novel throw-off key and its relation to said controller.

Figure 2 is a side elevation of the combined typewriting and computing machine, many well-known parts being omitted to clearly illustrate the invention.

Figure 3 is a perspective view of two registers, showing the throw-off key and associated mechanism for one register in operated position, the similar parts for the other register being shown in normal position.

Figure 4 is a partial side elevation of a register, illustrating how the non-operation of the throw-off key permits the computing-pinion-engaging mechanism to be effective.

Figure 5 is a view similar to Figure 4, illustrating how operation of the throw-off key causes the operation of the computing-pinion-engaging mechanism to be ineffective to shift the computing pinions.

Figure 6 is a skeleton perspective, showing the several throw-off keys and associated mechanisms, the novel restoring means for the several state-controllers, and the organization of novel mechanism for operating the index-pin-restoring mechanism.

Figure 7 is a perspective view, illustrating how the throw-off-key mechanism may be operated to interlock with the state-controller and hold the same, even though said controller has not been released by withdrawal of its latches by the carriage.

Figure 8 is a rear elevation, showing details of an individual state-controller for one of the registers and the relation of the novel throw-off key to said details.

Figure 9 is a skeleton perspective similar to Figure 6, showing the operated position of the restoring means for the state-controllers, and showing how the restoration of a subtraction-setting rock-shaft is effected, and indicating the restoration of the several throw-off-key mechanisms.

Figure 10 is a partial side view, illustrating particularly the operated position of the index-pin-restoring devices.

Figure 11 is a perspective view, showing the improvements in the pin-setting linkages.

Figures 12, 13 and 14 are views showing details of devices for minimizing noise, Figure 12 being a front view of a cushioning device for the pin-bars, Figure 13 presenting a side view of said devices, and Figure 14 a top plan view of one of said devices.

Figure 15 is a front elevation, illustrating the novel arrangement for superposing the typewriting machine upon the computing mechanism.

Figure 16 is a top plan view, showing details of the means for ensuring a fully restored position of the pin-bars to secure proper meshing of the computing pinions, and also showing details of the noise-minimizing devices.

Figure 17 is a partial side view, showing de-

tails of the means for ensuring full restoration of the pin-bars, said means being shown in their normal positions.

Figure 18 is similar to Figure 17, and shows the operated position of the parts.

Referring to Figure 2, numeral-keys 20 on key-levers 21 when depressed operate the usual train to swing types 22 upwardly and rearwardly to print against a platen 23. Said platen is mounted in a carriage 24 arranged to advance in letter-feeding steps determined by escapement-mechanism 25 actuated in the usual manner when the types 22 print. Said carriage, propelled by the spring 26, is guided on rails 27 fastened to the typewriter-framework 28, which surmounts the framework of the computing mechanism. Alphabet-keys 29 on key-levers 30 operate similarly to the numeral-keys 20 and their levers 21 to swing alphabetical types to the platen. Behind the rear-most row of the usual four-bank typewriter-key-board, there is arranged a row of tabulating keys 31 on tabulating key-levers 32 (partly shown), connected as shown in Helmond Patent 1,858,447, dated May 17, 1932, to elevate denominational stops 33 into the path of a stop 34 settable along a rack 35 carried by the typewriter-carriage 24.

The numeral-key-levers 21 have each a pendant-stem 36, which, when said lever 21 is depressed, rocks a shaft 37 by engaging an arm 38 fast to said shaft and underlying said pendant-stem 36. Said shaft 37 and its arm 38 form part of the usual Underwood indexing mechanism. There is one shaft 37 and arm 38 for every numeral-key 20, that is, for every digit from zero to nine, inclusive. Each shaft has an upwardly-extending arm 39 fastened thereto, whereby rocking of said shaft shifts a transverse horizontal bar 40 endwise to depress another transverse horizontal bar 41 edgewise. The endwise movement of bar 40 is translated into downward edgewise movement of bar 41 by bell-cranks 42, which link said bars 40, 41, at their ends, to form a parallel motion linkage, seen in Figure 11.

The pin-setting rock-shafts 37 are journaled in plates 64 forming front and rear sides of a frame for the pin-setting mechanism, said frame including side bars 65, Figure 11, to the ends of which said plates 64 are fastened. A common fulcrum-rod 66 serves for all the bell-cranks 42 at each side of the pin-setting linkages, each rod 66 being retained between the plates 64. The side bars 65 have slots 67 for guiding and spacing the ends of the depressible pin-setting bars 41. Springs 68 pulling upon the upper bars 40 yieldably hold the pin-setting linkages in normal positions. The assembled pin-setting frame is retained between side members 70 of the computing-mechanism framework by screws 71, Figure 16, spacers 72 locating the pin-setting frame sideways and facilitating its easy removal.

When the machines have more than three sets of pin-bars 44, the span of the bars 40, 41 between the bell-cranks 42 is proportionately greater, and, when setting pins in a middle set of pin-bars, 65 the pin-setting bars 41 are subject to upward deflection due to the increased span and the lightness of the bars. It is desired to maintain said lightness so as to minimize inertia and thereby conduce to lightness of key-touch. To overcome the upward deflection of the bars 41, there is fastened to each rock-shaft 37 an additional arm 69, which, as seen in Figure 11, may be formed integral with the arm 39 on said shaft. Said arm 69 has a tab 69a bent therefrom and 75 rounded, as shown, to overlie the pin-setting bar

corresponding to the rock-shaft to which the arm is fastened. Said arm may be of such length that, in the normal position of the rock-shaft 37, the tab 69a does not contact with the pin-setting bar 41, but does bear against said bar 41 when the rock-shaft is fully turned by the descending pendant-link 36, as shown in Figure 11. Figure 11 shows four sets of pin-bars to illustrate how the new arms 69 afford supports intermediate of the bell-crank supported ends of the bars 41, it 10 being understood that each rock-shaft 37 may have one of the additional arms 69, each having a tab 69a.

Downward movement of a digit-bar 41 as effected by operation of a numeral-key 20 is utilized 15 for depressing a corresponding digit-pin 43 in a pin-bar 44 extending from front to rear of the computing mechanism, and having at its forward end a rack 45 for rotating a computing pinion 46, to which a dial-wheel 47 is fixed. There are ten 20 digit-pins 43 in every pin-bar 44, there being one of the latter for every computing pinion 46. The computing pinions 46 are arranged in sets to constitute registers, each set of pinions having a corresponding set of pin-bars or drivers 44. As set 25 forth in aforesaid application No. 324,353, each pin-bar rack 45 has permanently in mesh therewith an idler 48 which may also act as a driver for the corresponding computing pinion 46, the pinions 46 of each set being normally out of mesh 30 from both the racks 45 and the idlers 48. The pin-bars 44 are guided for reciprocatory movement, at their front ends in a guide 49, and, at their rear ends, in a slotted comb-plate 50, the latter rising upwardly from a rear cross-member 35 51 of the computing-mechanism framework. Normally the pin-bars 44 stand in their retracted positions, so that their pins 43 are offset from the pin-setting bars 41, as seen in Figure 2. To enable a descending pin-setting bar 41 to depress a 40 pin 43, said pin-bar 44 is slightly advanced, so that its pins will directly underlie said pin-setting bars 41. This forward displacement of the pin-bars is effected seriatim in denominational order as the carriage passes step by step through a 45 computing zone.

As set forth in the aforesaid application No. 472,610, a single or trunk set of denominational trains is operable by the carriage and is ramified to the several sets of pin-bars, so that said carriage operating upon said trains may advance corresponding pin-bars of one or more sets of the latter, to position them under the pin-setting bars 41. The stop or dog 34, which is used for denominational tabulating, as aforesaid, is provided with a tappet 52 which rides over a row of jacks 53 bearing upon the upper ends of jointed rods 54. To ramify said rods to the different sets of pin-bars, a series of denominational rock-shafts 55 extend transversely of the 60 several sets of pin-bars 44, each rock-shaft having a rearwardly-extending master arm 56, to which a corresponding jointed rod 54 is connected, see Figure 2. Each rock-shaft 55 also has for each pin-bar group a pendant-arm 57, 65 the pendant-arms 57 on the rock-shafts collectively being thus arranged in groups corresponding to the groups of pin-bars which they serve. Each pendant-arm 57 has a forwardly-extending coupler 58 for advancing its pin-bar to indexing 70 position relatively to the digit-bars 41. Said couplers 58 swingable about their points of pivotal attachment to the pendant-arms 57 are normally positioned so that their forward ends are out of operative alignment with the pin-bars 44, 75

as seen in Figure 2 or Figure 17. That is to say, when said forward ends of the couplers 58 are down, a forward thrust of a coupler is ineffective to advance its pin-bar to pin-setting position.

To shift the groups of couplers 58 upwardly into effective positions, their forward ends are slidably retained in individually swingable bails 59. Thus each group of couplers 58 may be shifted upwardly as a unit, and the arrangement affords means for selectively calling into action different sets of pin-bars, and hence different sets of computing pinions 46. The selective shifting of the groups of couplers into effective positions is done by the carriage as it enters a computing zone. In one zone there may be required the operation of only one set of computing pinions 46, and hence the corresponding group of couplers 58 is shifted into position as the carriage enters said zone. Similarly, in another zone, two sets of computing pinions may be required to effect the computation, and hence two corresponding sets of couplers 58 will be shifted into position. Each stop or dog 34 is therefore provided with one or more tappets 60, to depress jointed rods 61, and thereby rock corresponding levers 62 to elevate corresponding coupler-shifting bails 59, the latter being connected to said lever 62 by links 63.

For each set of computing pinions, there is, therefore, an individual train including the parts just described for shifting its corresponding group of couplers 58 into effective position when desired in a certain computing zone. The drawings, generally, show three registers, and hence, as shown in Figure 6, there are indicated three sets of coupler-shifting trains, which, in fact, constitute register-selecting trains.

As the typewriter-carriage is tabulated to a computing zone, the dog 34 corresponding to said zone co-operates with the selected decimal-tabulating stop 33 to position said carriage in the desired computing column. For whatever register or registers it is desired to operate in said zone, there is a corresponding tappet 60 on said dog 34. If only one register is to be operated, then there is only one tappet 60. If two or more registers are to be operated, there are two or more tappets positioned in the several available slots in the dog 34, according to which particular registers it is desired to operate. As soon as the carriage enters a computing zone, one or more tappets 60 depress corresponding vertical slides 73, to depress the jointed rods 61 for elevation of corresponding coupler-shifting bails 59. The carriage having been tabulated to the desired denominational column, a corresponding denominational rod 54 will have been depressed to advance the corresponding pin-bar 44 to pin-setting position. Upon operation of a numeral-key 20 to type the first digit, a corresponding digit-pin 43 is set and the carriage escapes to the next denominational position, releasing the previously depressed rod 54, and, in turn, depressing the next rod 54, so that the next pin-bar 44 is advanced to pin-setting position under the digit-bars 41. The second digit is then typed, there being an accompanying setting of a digit-pin 43 followed by escape of the carriage to the next denominational position.

Thus, the indexing of the pin-bars 44 proceeds seriatim in denominational order as the carriage moves step by step through a computing zone. At each forward step of the carriage, the previously advanced pin-bar 44 is released

and returns to its normal retracted position under the pull of a spring-pressed lever 74, best seen in Figure 17, there being one of said levers 74 for each pin-bar, each lever having a projecting pin 75 which bears against a corner 76 of the pin-bar to retract the latter after its pin has been set and the carriage escapes to advance the next pin-bar to pin-setting position. The carriage advances toward the left, the highest denomination of the series of jointed rods 54 being therefore at the right. Inasmuch as the pin-bar of highest denomination is at the left of its group, the necessary denominational transposition is obtained by suitable arrangement of the pedant-arms 57 on the denominational rock-shafts 55, as set forth in said application No. 472,610.

The amount having been typed and the corresponding pins 43 having been set in one or more sets of pin-bars 44, the computing mechanism is cycled to shift the selected groups of computing pinions 46 into mesh either with the racks 45 or with the idlers 48, this shifting taking place at the very beginning of the cycle and preceding advance of the pin-bars 44. Such advance of the pin-bars will thereupon in the continuation of the cycle rotate the dials 47 to extents determined by whatever pins 43 were depressed in the several pin-bars plus extra carrying steps determined by a carrying mechanism, not shown, but set forth in my co-pending application No. 601,173, filed March 25, 1932 (now Patent No. 2,078,274, dated April 27, 1937).

The cycling mechanism includes a general operator formed by a pair of reciprocatory racks 78, guided along the inner sides of the side members 70 of the computing-mechanism framework, said racks being spanned by a cross-bar 79, the racks having fastened thereto side plates 80, to which the ends of said cross-bar 79 are attached, as seen in Figures 6 and 9. Said racks 78 are constrained to move in unison by means of a cross-shaft 81 journaled in the side members 70, and said cross-shaft has fastened thereto a pair of sectors 82, one for each rack 78, each sector being connected with its rack through an intermediate pinion 83, pivoted upon the adjoining side member 70. The racks 78 and cross-bar 79 thus form a reciprocatory carriage which may advance all of the indexed pin-bars and also restore the same. In any pin-bar, the depressed digit-pin 43 forms a downwardly-extending lug which lies in the path of a finger 85, Figures 17 and 18, formed on the end of a lever 86, pivoted upon the cross-bar 79.

The forward and rearward reciprocation or cycling of the cross-bar 79 for operating the pin-bars 44 may be effected in any suitable way, as for example, by a handle on the cross-shaft 81, as shown in the patent to Hanson, No. 1,278,812, dated September 10, 1918, or by a motor connected by a clutch to a driver 77 engaging one of the racks 78, as shown in the Hart Patent No. 1,171,403, of February 8, 1916.

When the cross-bar 79 advances, there is first an idle period in said advance, as will be evident from an inspection of Figures 17 and 18, which show the highest pin to be depressed, and which also show that there is a substantial gap between the finger 85 and said highest pin which must be taken up by the advance of the cross-bar before the latter can advance the pin-bar. This idle period of the cross-bar advance affords time for meshing the computing pinions either with the racks 45 or the idlers 48. The arms 87 of the levers 86 are backed up by a novel cushioning de-

vice in the form of a coil-spring 88 as the fingers 85 strike the depressed digit-pins 43, this cushioning device substantially minimizing the noise of the impact, and thus conducing to quiet operation of the machine. Detail description of said cushioning device and other similar devices will be made later on. The lever 86, of which there is one for each pin-bar, is part of the carry-over mechanism, and briefly described, its function is to advance a pin-bar an extra carrying step. To do this, said lever is caused to be rotated in a counterclockwise direction in which its finger 85 moves forwardly from the cross-bar 79 to effect said extra step.

15 The indexed pin-bars 44 having been fully advanced, the computing pinions 46 are next unmched from the racks 45 or from the idlers 48 before said pin-bars may be returned. For effecting the return of the pin-bars 44, the cross-bar 79 in its return movement engages downwardly-extending lugs 90 of said pin-bars, and carries the advanced pin-bars backwardly with it. At the beginning of the cross-bar return movement there is also an idle period before said cross-bar reaches any lug 90, said idle period affording time for the unmaching of the pinions 46. The rear face of the cross-bar also has a cushioning device in the form of a coiled spring 91 to minimize the noise of the impact against the pin-bars.

20 The cross-bar 79 does not itself fully return the pin-bars, the completion of the return being effected by the aforesaid spring-pressed levers 74, which, when the pin-bars are returned as far as the cross-bar 79, can carry them, snap over the corners 76 of said pin-bars, and move the latter farther until they strike the comb-plate 50, which also has a cushioning device in the form of a coiled spring 84 to absorb the shock of the impact. Thus there is left between the lugs 90 of the fully returned pin-bars and rear face of the cross-bar 79 a gap 92 which affords room for the aforementioned slight advance of the pin-bars to pin-setting position.

25 For shifting the computing pinions 46 into or out of mesh, each set of pinions mounted on an arbor 94 is retained in a shiftable frame 95, Figure 1. Each shiftable frame includes side plates 96, spaced apart by the arbor 94 and by a tie-rod 97. The several frames 95 are each retained sidewise between plates 98, rising from a front cross-member 99 of the computing-mechanism framework, each pair of said plates 98 being spanned by a tie-rod 100, upon which the idlers 48 may rotate. Between said plates 98 the pin-bar guide 49, Figure 2, is also retained. The shiftable frame-plates 96 have slots 101 which embrace flattened collars 102 loose on the tie-rod 100, said slots 101 standing horizontally when the shiftable frame is in such position that its computing pinions 46 are unmched from racks 45. Thus the rear end of the frame 95 is supported on the tie-rod 100. The forward end of the frame 95 is supported by an arm 103 extending rearwardly from a main rock-shaft 104, said arm having a slot 105 embracing the tie-rod 97, said slot extending horizontally when the arm is in normal position. Thus each frame by means of the slots 101 and 105 is guided for forward and backward movement to mesh and unmash the computing pinions 46 with and from the idlers 48. Downward and upward movement of the pinions 46 to mesh and unmash with the racks 45 is effected by swinging the arm 103 downwardly and upwardly, said arm, however, being loose on the rock-shaft 104 and being connectible thereto by 75 selectively operable coupling means, as set forth

in my aforesaid application, Serial No. 607,275, and which means will be presently described. Similarly, vertical arms 106, one on each side of the frame 95, are connected by a cross-bar 107 to form a bail 106^a, which is also loose on the rock-shaft 104, but which may be connected to said shaft by said coupling means. The vertical arms 106 are connected to the frame 95 by links 108.

For connecting either the horizontal arm 103 or the bail 106^a to the rock-shaft 104, there is provided for each register a sliding coupler, see Figure 1, on said shaft formed by a cross-bar 109 having downwardly-extending ears 110 at each end, so that the coupler may slide lengthwise of said shaft. The cross-bar 109 of each coupler has a rearwardly-projecting lug 111 to engage the horizontal arm 103. The ears 110 of said coupler have each a forwardly-extending lug 112 to underlie the cross-bar 107 that connects the pair of vertical arms 106. The coupler, generally indicated by 113, is keyed to the rock-shaft by means of a key 114 fastened to said rock-shaft, said key having a notch 115, which slidably fits over the coupler-bar 109. Said key 114 has a rearward extension 116, from which there projects a pin 117 normally underlying and abutting the horizontal arm 103. Springs 134, Figure 1, uphold the computing-pinion-shifting frame 95 when the pin 117 recedes from the horizontal arm 103 in the rocking of the shaft 104. Said pin 117 will so recede when the subtraction-bail 106^a is coupled to said rock-shaft 104, or when the register is neutral during rocking of said shaft during a cycling operation. There is one of said springs on each side of the frame 95. Studs 89 on said frame 95 abut edges of stops 93, said springs 134 pulling on said studs, and being connected to said stops as shown, said stop-edges permitting sliding of said studs therealong as the frame 95 is shifted rearwardly and forwardly for subtraction. The key 114 also has a forward extension 118, which is received in a slot 119 of the bar 107 of the subtraction-bail 106^a. By means of said extension 118, said bail 106^a is retained lengthwise of the rock-shaft 104, and said extension also serves to restore said bail after it, together with the rock-shaft, has been rocked to mesh the pinions 46 with the idlers 48.

The coupler 113 stands normally in such position (neutral), see Figure 1, that its lugs 111 and 112 are ineffective to rock the arm 103 and the arms 106, respectively, the bar 107 which connects said arms 106 having clearance notches 120, normally overlying the lugs 112, and the lug 111 in the neutral position of the coupler being to the left of the arm 103. Shifting the coupler to the right will cause its lug 111 to overlie the arm 103. In this case, the lugs 112 of the coupler will underlie the notches 120 of the bar 107. With the coupler thus shifted toward the right, clockwise rotation of the shaft 104 will swing the arm 103 downwardly, and cause the computing pinions 46 to be meshed with the idlers 48.

Shifting the coupler 113 to the left will present its lugs 112 to the lower edge of the bar 107 that connects the vertical arms 106. In this case clockwise rotation of the shaft 104 will swing said vertical arms 106 rearwardly and cause the pinions 46 to be meshed with the idlers 48.

With certain exceptions to be explained later, the position of the coupler 113 is determined by the carriage as it enters a computing zone. That is to say, there extends from said carriage a train operative to shift the coupler from its nor-

5   mal neutral position to either adding or subtracting position. This train includes for each register an elongate slide 124 extending from the rear to the front of the machine, and urged forwardly by a spring 125, the forward movement of said slide 124 being normally restrained by a latch 126, against which the rear edge of a notch 127 in said slide abuts. The latch 126 is guided, at its lower end, for vertical movement, in a plate 128, fastened to the bottom of the cross-member 51 of the computing-mechanism framework, and is further guided by a slotted block 130, fastened to the pin-bar-guiding comb-plate 50. Withdrawal of the latch 126 from the state-control trolley slide 124 of a register is effected when the pin-bar coupling bail 59 for said register is caused to be shifted upwardly as the carriage enters a computing zone. The latch 126 has its upper end 131 formed so that it may be engaged and lifted 10 by the bail 59. Withdrawal of the latch 126 causes the slide 124, under the pull of the spring 125, to move forwardly until the rear edge of a notch 133 in said slide strikes a second latch 132. The slide 124, moving forwardly until arrested 15 by the latch 132, will cause, by means presently to be described, the rock-shaft coupler 113 to be shifted to the right. The latch 132 constitutes a subtraction-latch. In other words, when said latch 132 is also withdrawn, the slide 124 will 20 advance further forwardly for causing the rock-shaft coupler 113 to be shifted toward the extreme left. Each slide 124, in order that it may shift its rock-shaft coupler 113 to the right or the left, from a neutral position, has, at its forward end, a cam-head 135 in which there is formed a cam-groove 136, as seen in Figures 6 and 9. Co-operating with said cam-groove 136 is a transverse slide 137, having a lug 138 embraced by said cam-groove. Said slide 137 is 25 mounted for endwise movement, parallel to the rock-shaft 104, on a plate 139 extending across the front of the cross-member 50 of the framework of the machine. Each slide 137 has slots 140 slidably fitting collars 141, projecting from said plate 139. The slides 137 do not rock, but they may, nevertheless, shift the rockable rock-shaft couplers 113. Each slide 137 has, therefore, a notch 142 to receive an ear 143 of its coupler 113, said notch 142 being deep enough 30 to permit the coupler to be rocked with its shaft 104. In the neutral positions of the slides 124, 137, the lug 138 occupies the dwell at the forward end of the cam-groove 136, as seen in the two cam-grooves at the right of Figure 6. From said dwell, the cam-groove slants to the right, to terminate in another dwell-portion 144 which is occupied by the lug 138 in the intermediate position assumed by the slide 124 upon withdrawal of the addition latch 126 alone. In this position 35 the slide 137 and coupler 113 will have been shifted to the right, causing the horizontal arm 103, now overtopped by the lug 111 of said coupler, to be coupled to the rock-shaft 104, as aforesaid. From the dwell 144, the cam-groove slants to the left to terminate in another dwell 40 146, which is occupied by the lug 138 when the subtraction latch 132 has been released also. The slide 137 and coupler 113 will then have been shifted to the extreme left, causing the subtraction-ball 106*, which includes the vertical arms 106, to be coupled to the rock-shaft 104, the lugs 112 of the coupler then abutting the lower edge of said bail 106*, and the lug 111 being clear of the horizontal arm 103.

45   75   The addition latches 126 are withdrawn indi-

vidually, that is, the withdrawal of one of said latches accompanies the selection of a register through elevation of the pin-bar coupler-bail 59 by the carriage as the latter enters a computing zone. The subtraction-latches 132 for the several registers are withdrawn simultaneously either automatically as the carriage enters a computing zone, or by means of a manually operable subtraction-key 148 and a train operated thereby. For simultaneous withdrawal of the subtraction-latches 132, there is provided a rock-shaft 149 journaled in the side members 70 of the framework, or in any other suitable member of said machine. Said rock-shaft 149 has fastened thereto arms 150, to which the upper ends of the subtraction-latches are connected. The general subtraction-key 148 is slidably guided in a front portion 151 of the casing, and has a rearward extension or bar 152 guided on a stud 153 projecting from the framework side member 70, said bar having an elongate slot 154, which slidably fits said stud. Rearward movement of key 148 and its bar 152 is against the pull of a key-retracting spring 145, and rocks the shaft 149, said shaft having fastened thereto a forwardly-extending cam-arm 155, whose cam-shaped end is engaged and displaced by a roll 156 on the subtraction-bar 152. The shaft 149, when rocked by operation of the subtraction-key 148, is held by a latch 157, said latch engaging an arm 158 20 fastened to said rock-shaft. This latch 157 is useful when the subtraction-key 148 is pressed before any of the addition-latches 126 have been released.

25   For enabling the carriage to effect withdrawal 35 of the subtraction-latches 132, the dog 34 for a zone in which it is desired to effect automatic subtraction, has an extra tappet 160 for depressing a slide 161 forming the end of a train that releases a lever 162, for rotation by a spring 163, 40 said lever having a pin 164 to engage a cam-arm 165 fastened to the rock-shaft 149.

30   The lever-releasing train includes a horizontal latch 166 guided at one end in a plate 167, so that said end may normally uphold an arm 168 of the 45 lever 162, see Figure 9. Coupled to the other end of the latch 166 is a vertical arm 169 connected by a short shaft 170 to a horizontal arm 171 from which extends upwardly a rod 172 to the carriage engaged slide 161. As indicated in Figure 50 6, when the carriage enters a computing zone, the latch 166 is caused to be withdrawn by the train of parts just described, the lever 162 is released to rotate the rock-shaft 149 and the subtraction-latches 132 are all withdrawn. The 55 lever 162, after having sufficiently rocked the shaft 149, by co-operation of the lever-pin 164 and cam-arm 165, abuts a pin 173. When the shaft 149 is automatically rocked by the carriage the functioning of the latch 157 is of no moment. 60 Restoration of the lever 162 results when the computing mechanism is cycled, after the carriage has passed the slide 161. The general-operator cross-bar 79, in its advance stroke, depresses the usual cam-arm 162* of said lever to 65 rotate the latter and raise its arm 168 above the horizontal latch 166. Said latch thereupon, urged by a spring 170* snaps under said arm 168, and the rock-shaft 149, freed from said lever 162, resumes its normal position in a manner which 70 will be described later.

75   The state-control slides 124 have pins 175 which when said slides are in their extreme forward positions, that is, subtracting positions, stand behind a universal restoring bar 176, which 75

during the cycling of the machine is moved rearwardly to effect restoration of the cam-slides 124 that have been released.

- It will be seen now that the positions of the several slides 124 determine whether their respective registers remain neutral during the cycling operation or whether the computing-wheel shifting means are conditioned for addition or subtraction. That is to say, the positions of said slides determine whether the horizontal addition-arms 103 or the subtraction-bails 106^a will be coupled with the rock-shaft 104 during the cycling operation or whether neither will be so coupled.
- For actuating said rock-shaft 104, there is coupled to the general operator a shaft 177, the coupling being effected by a double-clutch device to give a full revolution to said shaft in each cycle, as set forth in application No. 324,353. Said clutch device (not shown) has a pair of opposite single-tooth ratchets, geared to the cross-shaft 81 and a pinion 178, Figure 6. A driven member of said clutch is keyed to the shaft 177, and, in the forward stroke of the general operator, is driven by one ratchet and in the reverse stroke by the other ratchet in a manner to impart a full revolution to said shaft 177. The rock-shaft 104 has fastened thereto an upwardly-extending arm 179, Figure 3, to which is connected a link 180 extending to the full-revolution shaft 177. The full-revolution shaft 177 has fastened thereto a cam 181 against which a roller 182 projecting from the side of the link 180 bears. The link has a rectangular hole 183 slidably fitting a block 184 which has a loose fit on the shaft 177, said link 180 thus being, by means of said block 184, slidably supported by said shaft 177. A cam 185 that is complementary to the cam 181 is also fastened to the shaft 177 and has a co-operating roll 186 projecting from the opposite side of the link 180, the cams 181, 185 and their rollers co-operating to reciprocate the link 180 positively in opposite directions in a full revolution of the shaft 177. The cams 181, 185 face opposite sides of the link 180 and retain the same laterally of the shaft 177. The cams 181, 185 are so formed that at the beginning of the general-operator cycle, there is a quick rearward displacement of the link 180 to rock the shaft 104 and engage the computing pinions 46 either with the racks 45 or with the idlers 48 before the racks advance. Thereafter a dwell 187 of the cam 185 maintains the link 180 against forward displacement, the cam 181 having a complementary dwell. These dwells are relatively coextensive with the advance of the pin-bars 44 to rotate the pinions 46, said advance including the aforesaid extra advance effected by the carrying mechanism. At the completion of the carrying operation, the cams 181, 185 quickly shift the link 180 forwardly, thereby causing the rock-shaft 104 to be rotated counterclockwise for disengagement of the computing pinions 46 from the racks 45 or idlers 48.
- The novel throw-off-key mechanism operates to restore any state-controlling slide 124 that may have been caused to be released by the carriage alone or by both said carriage and the operation of the manual subtraction-key 148. For each register, there is provided a throw-off key 190 having a plunger-like bearing in the front casing 151 of the computing mechanism, as seen in Figure 6. Each key 190 has within said casing an extension 192 articulated with an arm 193 of a bell-crank 194 which is loosely

mounted on the rock-shaft 104. Said bell-crank arm 193, in a midway position of the bell-crank 194, extends substantially parallel with the slanted surface of the casing 151 through which the key 190 projects. Each bell-crank has a downwardly-extending arm 196 articulated with a slide 197, as seen in Figure 3, so that depression of the throw-off key 190 will move said slide forwardly. Forward movement of the slide 197 turns a bell-crank 198 pivoted to the bottom of the cross-member 99 of the framework, see Figure 2. Into said bottom of the framework there is threaded a shoulder-screw 195 having a collar 199 over which slidably fits a slot 200 of the slide 197, said collar also forming the pivot for the bell-crank 198 which is between the bottom of said cross-member 99 and the top of the slide 197, the shoulder-screw having a broad head 201 against which the under surface of the slide 197 may bear. At its forward end the side 197 is guided and supported in a slot 202 of the plate 139. The bell-crank 198 has a slotted arm 203 embracing a pin 204 projecting from the state-controlling slide 124. Another arm 205 of said bell-crank 198 is for engagement by the slide 197, said arm having a downwardly-projecting semi-circular stud 206, as seen in Figure 3. With the state-controlling slide in either of the dotted-line positions indicated in Figure 6, the bell-crank 198 will have been rotated so that its stud 206 is within the path of a cam 207 formed in the side of the slide 197. That is to say, if said cam-slide 197 is moved forwardly by operation of the throw-off key 190, said cam 207 engaging the pin 206 will rock the bell-crank 198 and thereby shift the state-controlling slide rearwardly. As the elimination key is pressed downwardly, the slide 197 moves forwardly and rotates the bell-crank 198, and when a latch-edge 208 of said slide 197 overtakes the semi-circular stud 206, the latter, being on the bell-crank 198 which is connected to the slide 124, will, under the influence of the slide-spring 125, seat itself into the notch 209 forming said latching edge 208, the throw-off key 190 having been pressed far enough to effect this result, the movement being limited by abutment of the rear end of the slot 200 with the collar 199. A spring 210 pulling upon the slide 197 will draw said slide, when the operator's finger is released from the key 190, against the straight portion of the semi-circular stud 206, as seen at the register on the right of Figure 3. In this manner, the state-controlling slide 124 is locked in its neutral position by operation of the throw-off key, the spring 125 urging the bell-crank 198 in a clockwise direction, as seen in Figure 3, so that the slide 197 cannot escape rearwardly. When the state-controlling slide for a certain register is so locked in neutral position by operation of the throw-off key 190, the rock-shaft 104 will during a cycling operation rock idly with respect to said register, as indicated in Figure 5; that is, the computing pinions 46 are not shifted into mesh with the racks 45 or idlers 48, but remain in their normal unmeshed positions during the cycle. In this manner, the register is silenced by operation of its throw-off key. Figure 4 indicates that with the throw-off key not operated, rocking of the shaft 104 will shift the computing pinions 46 downward to mesh with the racks 45, it being, according to said Figure 4, assumed that the state-controlling means are set for addition. To enable the slide 197 to escape rearwardly and thereby effect restoration of the throw-off-key mechanism, the

state-controlling slide 124 in the restoration thereof by the bar 176 is moved back far enough to swing the bell-crank 188, so that its semi-circular stud 206 withdraws from the notch 208 of the slide 187. The latter will then, under the pull of the spring 210, snap rearwardly and the state-controlling slide will be free to assume a forward position again. Rearward movement of the slide 187 may be limited by abutment of the front end of the slot 200 with the collar 199. It will be evident that the throw-off-key mechanism may also be operated while the state-controlling slide 124 is in neutral position. In this case the slide 124 will move rearward slightly as the semi-circular stud 206 overtakes the latching edge 208, and will then settle back in its normal position as said stud seats itself in the notch 209. Thus said throw-off-key mechanism may be operated at any time, that is, before or after the typing of an amount or even before the carriage is tabulated to a new zone in sequence to computation in a preceding zone, it being understood that said computation must, however, be first completed. It will be seen now that the operative, by selectively pressing the sub-control or throw-off keys 190, may on occasion differentially depart from the computing program that otherwise is carried out automatically under control of the primarily set carriage-tappets 60, 160. Having merely pressed one or more of said keys 190 according to the desired departure from said program, the companion key-trains or means become automatically detained in operative positions, and the operative need do nothing further to determine said departure or its conclusion, since the necessary resumption of the original program is effected automatically by means of the general operator when the latter is cycled for whatever computation, in one or more registers, is made at said departure. Said departure is thus made definitely temporary, and misoperation to which the machine would be liable, if the operative had to see to each restoration of the differentially settable throw-off-key devices, is avoided.

The universal restoring bar 176 for the several state-controlling slides 124 is driven rearwardly by means of a rock-shaft 212, which also serves to effect restoration of the digit-pins 43 at the end of the computing cycle. Said shaft may be journaled in the side members 70 of the computing-mechanism framework, as indicated at 213, Figure 6. Said shaft is rocked positively in pin-restoring and slide-restoring direction by the cross-bar 79 as the latter nears the end of its return stroke. Fastened to the rock-shaft 212 is an arm 214 extending upwardly, and having pivotally connected thereto a link 215 extending rearwardly, the rear end of said link being slidably received in a slotted plunger 216 working in a thimble 219 driven into the cross-member 51 of the framework, said plunger being urged upwardly by a spring 217, Figures 2 and 9. Said spring 217 presses the link 215 against the bottom of the cross-bar 79, so that after said cross-bar is advanced past a hook 218 of said link, Figure 9, said hook will, when the cross-bar returns, be in the path of a plate 220, fastened to the bottom of said cross-bar 79. It will be seen from Figure 9 that as the cross-bar 79 completes its return movement, the rear edge of its plate 220 will have caught the hook 218 of the link 215 and carried the latter rearwardly, causing the rock-shaft 212 to be rocked positively. Just before the cross-bar 79 reaches the end of its

return stroke, the rear end of the link 215 is depressed, causing the hook 218 to escape from the plate 220, whereupon a spring 222 will urge the link 215 forwardly again; this mechanism will be explained in more detail later. Said spring 222 may be attached to the middle of the universal bar 176, which is connected to a pair of arms 223, fixed to the rock-shaft 212 by a pair of links 224. It will now be seen that as the general-operator cross-bar 79 rocks the shaft 212, said universal bar 176 will be moved rearwardly, and, by means of the pins 175 in the several state-controlling slides 124, will restore the latter. As the several slides 124 are thus restored, their respective pairs of latches 126 and 132, if free to do so, will drop into notches 127, 133, and hold said slides in neutral position as the universal bar 176 moves forwardly again under the pull of the spring 222 when the link 215 escapes. Forward movement of the universal bar 176 is limited by an abutment 225 fastened to a bar 226 extending forwardly from the cross-member 51, and having at its forward end a hook 227, so that said bar 226 may thereby support the rock-shaft 212, as seen in Figure 6. The resiliency of said abutment 225 minimizes the noise as the universal bar 176 strikes against the same.

The universal bar 176 is adjustable rearwardly and forwardly with respect to its position at the end of its rearward stroke, and, to this end, its connection with the links 224 is made by means of shouldered collars 211 fitting holes in said bar 176, and having eccentric holes through which pass screws 221, threaded into said links 224, as seen in Figure 6. It will be seen that by loosening said screws 221, the eccentric collars 211 may be turned, and the bar 176 thereby adjusted rearwardly or forwardly, after which said screws 221 are tightened again.

As shown in the aforesaid application No. 324,353, or in the application of Thieme, No. 563,033, filed September 16, 1931 (now Patent No. 2,075,557, dated March 30, 1937), the zero digit-pins of all the pin-bars 44 are normally depressed. When a pin of higher value is set in any bar, the zero-pin of said bar automatically becomes restored. Conversely, to effect the restoration of any higher pin, the zero-pin is reset, the restoration of the higher pin then occurring automatically. For facilitating co-operation with universal pin-restoring means about to be described, each zero-pin may be depressed by operation of a lever 229, Figure 2, pivoted to the side of each pin-bar 44. One arm of said lever is articulated with the zero-pin at 230, and an opposite arm terminates in an edge 231 positioned below the edge of the pin-bar 44. Pivoted between each pair of the side plates 98 that guide the computing pinion frame is a bail 233 which includes a cross-bar 234. The arms of said bail have downward extensions 235 reaching toward an arm 236 fastened to the rock-shaft 212. Spanning said downward extensions 235 are tie-rods 237 in the path of said arm 236. As the shaft 212 is rocked by the general operator, it will be evident that the shaft-arm 236 striking the tie-rod 237 will rock the bail 233 about its pivot 238, thereby causing the bail-bar 234 to move upwardly. It will also be evident that this upward movement of the said bar 234 takes place at about the time when the pin-bars 44 are near the end of their return movement, that is, when the edges 231 of the levers 229 are over the bar 234, and that said bar 234 will therefore be enabled in its upward movement to rock the levers 229, depress the zero-pins 43 that are

not depressed, and thereby effect restoration of the higher pins 43 that were set. The bail-bar 234 may have a bevel 239 graded to the contact of said bar with the edges 231 of the zero-pin-levers 228. There are one of the bails 233 and an arm 236 for each set of pin-bars.

For depressing the restoring link 215 at the end of a cycle to effect its escape from the general-operator cross-bar 79, it being noted that 10 said escape will also cause the pin-restoring bails 233 to move downwardly again under their own weight, there is pivoted to the side of the left computing frame-member 70 a lever 240, Figures 2 and 6. Said lever is urged counterclockwise by 15 a spring 241, so that a roll 242 on an arm of said lever normally rests in a notch 243 of one of the general-operator racks 78 when the latter are in normal position. As soon as the general operator moves forwardly, it will be evident that the 20 lever 240 will be rocked clockwise. Conversely, as the general operator nears the end of its return stroke, the roll 242 will drop into the notch 243 again, after riding idly along the top edge of the rack 78. The reverse movement of the lever 240 thus occasioned as roll 242 drops into the notch 243 again at the end of the return stroke of the 25 general operator is used to depress the restoring link 215, and, to this end, said lever 240 has a lateral arm 244 fastened thereto which bears on 30 the link 215, and depresses the same at said end of the general-operator stroke.

The arm 244 is bent from a blank 246 adjustably fastened to the lever 240 by screws 247. The lever 240 also serves to raise the latch 157 that 35 holds the subtraction cross-shaft 149, said lever having an upwardly-extending arm 248, carrying a pin 249, to lift a cam-arm 250, which is part of said latch. The lever 240 being rocked clockwise as soon as the general operator starts forward, the latch 157 is thereby lifted by pin 249 bearing against the cam-surface of arm 250, whereupon the shaft 149 urged by a spring 251 rotates to restore the subtraction-latches 132 to the state-controller slides 124. The lower ends 40 of said latches 132 will then bear upon said slides 124, ready to snap into the notches 133 as soon as the slides 124 are restored. One end of the spring 251 is fastened to a collar 121 keyed to the shaft 149, Figure 6, the other end reacting 45 against an arm 122 loose on said shaft, and retained between a block 123 and the cam-arm 165, which is fastened to, but spaced from, said block, said block being fastened to said shaft. By this arrangement the spring 163, in rotating 50 the lever 162, to rock the subtraction-shaft, is not opposed by the spring 251. The restoration of the slides 124 is completed as the general operator completes its return stroke, as shown in Figure 9, in which the arm 244 bearing down 55 on the link 215, due to the reverse rotation of the lever 240 as its roll 242 re-enters the notch 243, is about to depress said link, and thereby disengage its hook 218 from the plate 220. In Figure 10, when said hook 218 is just about to 60 escape from said plate 220, the rock-shaft 212 will have been rocked in the direction of the arrow to not only move the universal bar 176 rearwardly, to restore the state-controlling slides 124, but to also cause the resetting of the digit-pins 43 by elevating the bails 234. Upon restoration of the state-controller-slides 124, the addition latches 126 also re-enter their notches 127 if their respective pin-coupler bails 59 are down. Said slides 124 are guided and supported at their 65 rear ends by headed shoulder-screws 252, one on

each side of each slide 124, threaded into the framework-cross-member 51, said screws also securing the plates 128 that guide the lower ends of the several pairs of latches 126, 132. At their forward ends said slides 124 are guided in slots 5 253 of the plate 139.

When the computing pinions 46 are to be shifted into mesh with the racks 45 or idlers 48, the teeth of said racks must be in transverse alignment and in proper position. In other words, the pin-bars must all be fully restored against the comb-plate 50. To insure this proper alignment, the following mechanism is provided. Each pin-bar 44 has a notch 255, Figures 17 and 18, within which plays the lower edge of a blade 256, extending across the several sets of pin-bars 44, as seen in Figure 16. The ends of said blade 256 have pivots 257 received in elongated bearing-holes 258, Figure 17, in brackets 259, which may be fastened to the rear member 64 of the pin-setting frame. Said pivots 257 are at the top of the blade 256, and normally rest on the bottom of their bearing-holes 258, the lower edge of the blade being thus swingable rearwardly from a normal position to which the blade is urged by a 25 spring 260. In said normal position, see Figure 17, the lower edge of the blade is advanced from the rear edges of the notches 255 of the fully restored pin-bars 44, so that the latter may receive their usual slight advance to pin-setting 30 position. It will be seen that if any pin-bar is not fully restored, swinging the blade 256 rearwardly will fully restore said pin-bar. It is thus evident that the blade 256 extending across all 35 the pin-bars 44 is effective to transversely align all the pin-bars, so that the computing pinions may mesh properly with the racks 45 or idlers 48. By means of the aforementioned lever 240, which, it will be remembered, is rocked at the very beginning of the general-operator cycle, the 40 blade may be swung rearwardly to align the pin-bars. On the same stud 153 that carries the subtraction-shaft-latch 157, there is pivoted a lever 261, having a cam-arm 262 similar to the cam-arm 250 of said latch. Thus, when the lever 240 is rocked, its pin 249 will lift said cam-arm 262 of the lever 261, and rock the latter, which has an arm 263 reaching toward the blade 256, said arm 263 having a stud 264 for engaging a finger 265 fastened to said blade 256, and thus 45 swinging said blade rearwardly, to insure alignment of the pin-bars 44. The pin-bar alignment having been assured by such swinging of the blade 256, the latter is caused to be lifted to clear the pin-bars, so that the latter may be advanced to 50 rotate the computing pinions 46 as the general operator continues its advance stroke. It will be understood that the blade is swung rearwardly before the computing pins are shifted into mesh, the timing of the computing pinions-shifting 55 cams 181, 185 on the full revolution shaft 177 being made accordingly. The interval before the general-operator cross-bar 79 picks up a depressed digit-pin 43 is ample to permit shifting the computing pinions in sequence to the swing- 60 ing of the blade 256.

For lifting the aligning blade 256, there is fastened to the general-operator cross-bar 79 a pair of runners 267, one near each end of said blade, as seen in Figure 16. As seen in Figures 70 75 and 18, said runners have, at their front ends, camming bevels 268, which may engage the lower edge of the rearwardly-swung blade 256, and which, as said cross-bar 79 advances, force the blade upwardly until it clears the pin-bars. 75

Thereafter, as the cross-bar 19 continues its advance, the blade 256 continues to be upheld, clear of the pin-bars, by the top edges of the runners, which, as seen in Figures 17 and 18, extend rearwardly far enough to uphold the blade throughout the advance stroke of said cross-bar 19. The cam-bevels 268 may be so positioned that while the blade is being swung back to align the pin-bars, it is also being lifted, the lower edge of said blade just emerging from contact with the rear edges of the notches 255 when said blade has swung back far enough to align the pin-bars against the comb-plate 50, in which the rear ends of the pin-bars are guided. At intermediate points between the brackets 281, the aligning blade 256 is provided with studs 270 projecting toward the plate 64, and having rounded ends for abutting said plate as the blade swings. Said blade 256 is thus braced by said studs 270 against forward deflection as it swings back to align the pin-bars.

For supporting the typewriter close to the computing mechanism, the side members 70 of the computing-mechanism framework have, fastened along their top edges, brackets 281, Figure 15, secured to lugs 282 of the side members 70 by screws 283, and extending inwardly far enough to underlie the base of the typewriter-framework. Screws 284 pass through said brackets 281, and are threaded into said base of the typewriter to hold the latter in place. Rising above the bottom of the typewriter, and from the top edges of the side members 70, are cover-pieces 285, extending from the sides of the typewriter outwardly until the outer sides are flush with the outer sides of the side members 70. The front ends of the cover-pieces 285 may be flush with the front casing 151, as indicated in Figure 6, and may extend rearward along the sides of the typewriter to blend in any suitable manner with the rear portions of the side members 70. The side cover-pieces 285 may be pressed out of sheet-metal, and may rest on studs 286 projecting upwardly from the brackets 281, and may be secured by screws 287 threaded into said studs. The space between the bottom of a side cover-piece 285 and the top of a bracket 281 affords room for controlling keys, as for example, the subtraction-key 148, the bar 152 of said key occupying said room for part of its length, and then being bent downwardly, and again rearwardly toward its rear supporting stud 153, as indicated in Figure 2. At the right side of the machine, the space between the cover 285 and the bracket 281 affords room for another key, as for example, the credit-balance key 288 of the Underwood bookkeeping machine.

For concomitant use with the computing mechanism, the typewriter may be provided with a series of registers and actuating devices of the type set forth in the aforesaid Kurowski patent, said registers and actuating devices overhanging the typewriter keyboard. Said registers are not shown, nor are the actuating devices, which are connected by partly shown links 290 to the numeral-key-levers 21. On account of the overhanging registers and actuating devices, shielded by a casing 289, operation of the tabulating keys 31 and numeral-keys 20 is impeded, that is to say, the operator's fingers may not readily give said keys a direct downward thrust. The operation of said keys is substantially facilitated by inclining the several rows of keys at graded angles. The keys 31 of the rear or tabulating row are inclined or tilted forward the most, at an angle of about 25 degrees from horizontal, and the

keys 20 of the next or numeral-key row being tilted forward at a less angle than are the keys 31, the keys 20 being tilted about 10 degrees. As the operator's fingers reach rearwardly to depress the keys in the rear rows, it is found that such graded tilting of the keys conduces substantially to ease of operation.

Figures 12, 13 and 14 show details of the cushioning devices associated with the pin-bars 44. As briefly mentioned heretofore, said cushioning devices include for the front face of the general-operator cross-bar 19 a spring 88 formed of a closely-wound helix of spring-wire extending across the several sets of pin-bars, as shown in Figure 16. Said coiled spring 88 is retained in a groove 285 cut in the front face of the cross-bar 19, the groove being of such depth that there may be placed behind the spring 88 a resilient backing 296, formed of leather, wood, hard felt or other suitable material, and so that the front of the spring 88 extends slightly beyond the front face of the cross-bar 19. For securing the spring 88 in place, there passes through the inside thereof a rod 297, long enough to project beyond the ends of the spring 88, so that said rod may be held 25 by clamping screws threaded into the cross-bar 19. The fingers 85 of the levers 86 that are pivoted to said cross-bar abut the coiled spring 88 when said fingers engage a depressed digit-pin 43 for advancing a pin-bar 44. The noise of the 30 impact of said fingers with the digit-pins 43 is substantially reduced, the impact reacting against the spring 88.

In a similar manner, when the cross-bar 19, in its return stroke, picks up the pin-bars, the noise 35 of its impact with the lugs 90 of said pin-bars is also substantially minimized by a spring 91. As seen in Figure 16, said spring is also of a length to span the several sets of pin-bars 44, and is secured in the same manner as is the spring 88, 40 said spring 91 having a rod 297, a backing 296 and rod-retaining screws 298. The springs 88, 91 may be additionally secured within their recesses 295 by staking over the edges of the recesses, as indicated at 299. Figures 12 and 16. 45

The comb-plates 50, in which the rear ends of the pin-bars 44 are guided, are also provided with cushioning devices to minimize the noise of impact of said pin-bars. As already mentioned, said devices include the coiled springs 84, one for 50 each comb-plate. The front face of each comb-plate has a transverse groove 300 cut deep enough, so that when the spring 84 is seated therein, it is secured against vertical displacement. An angle-piece 301 fastened to the rear face of each 55 comb-plate affords a bearing-surface for the pin-bars 44, and compensates for the reduction of such bearing in the comb-plate occasioned by cutting the recess 300 therein. An indentation 302 may be made in the pin-bar edge which formerly abutted the comb-plate to provide for sufficient retraction of the pin-bar. For holding the spring 84 in place, a wire 303 is threaded through it, and is long enough, so that its ends 60 304 may be bent around to hold against the rear face of the comb-plate 50, as shown in Figures 14, 16. The side edges of the comb-plate 50 may be notched, as indicated at 305, to receive the wire 303. 65

Certain features referred to herein are disclosed in my aforesaid co-pending applications Nos. 324,353, 472,610, 601,173, and 607,275; but no claim herein covers any of said copending applications. All of the claims specify improve- 70 75

ments which are not disclosed in any of said applications.

Variations may be resorted to within the scope of the invention, and portions of the improvements may be used without others.

Having thus described my invention, I claim:

1. In a computing machine having a register arranged for performing addition or subtraction, cycling mechanism, a carriage, and a spring-pressed state-controller releasable by said carriage to different positions to condition said register for addition or subtraction, the combination of a throw-off key, a train connecting said key and controller, whereby setting of said key 10 stores the released controller to neutral position or prevents its movement to effective position, said train including latching means to hold the controller neutral, and means whereby the latching means are disengaged at the end of a 15 cycling operation, to restore said train and thereby condition said controller for subsequent release by said carriage.
2. In a computing machine having a register arranged for performing addition or subtraction, cycling mechanism, a carriage, and a spring-pressed state-controller releasable by said carriage to different positions to condition said register for addition or subtraction, the combination of a throw-off key, and a train connecting said 20 key and controller, whereby setting of said key restores the released controller to neutral position or prevents its movement to effective position, said train including latching means to hold the controller neutral, said cycling mechanism 25 arranged to restore said controller slightly farther than its normal restoration, thereby disengaging said latching means to effect restoration of said train to normal position and thereby conditioning said controller for subsequent release by 30 said carriage.
3. In a computing machine, the combination with a series of computing pinions, a series of indexable reciprocating racks therefor, said pinions normally disengaged from said racks, and a general operator including a bar extending across said racks, said bar being reciprocatory to advance and return the racks, of spring-devices for returning said racks slightly farther than they are returned by said general-operator cross-bar, to permit slight advance of said racks seriatim 40 for indexing operations, each rack being returned by its spring-device after said slight advance for indexing, and means actuatable by said general operator at the beginning of its cycle to positively 45 force back any rack that is not restored by said spring-devices to assure alignment of the rack-teeth, said means arranged to withdraw from the racks after aligning same, so that they may be advanced by the general operator for rotating 50 said pinions.
4. In a computing machine, the combination of a set of indexable racks, computing pinions normally disengaged from said racks, a general operator to reciprocate said racks, spring-devices arranged to snap into said racks and return them 55 beyond the range of the general operator, so that said racks may be slightly advanced for indexing operations, a transverse blade positioned on edge and swingable to engage said racks to forcibly align any one not aligned by said spring-devices, and means whereby said general operator 60 so swings said blade at the beginning of a cycling operation, and whereby said general operator then lifts said blade from said racks to permit advance of said racks to rotate said pinions.

5. In a computing machine, the combination of a set of indexable racks, computing pinions normally disengaged from said racks, a general operator to reciprocate said racks, spring-devices arranged to snap into said racks and return them 5 beyond the range of the general operator, so that said racks may be slightly advanced for indexing operations, a transverse blade having pivots at its ends, bearings having slots for receiving said pivots, said bearings arranged to position said 10 blade on edge in engagement with said racks, and means whereby said general operator swings said blade at the beginning of a cycling operation to forcibly align any rack not aligned by its spring-device, and whereby said general operator then 15 moves said blade from said racks along said bearing slots to permit advance of said racks to rotate said pinions.

6. In a computing machine having a carriage, the combination with a set of computing pinions, indexable drivers therefor, and a general operator for the drivers, and a spring-driven state-determining member releasable by the carriage to determine co-operation of said pinions and drivers during a general-operator cycle, of a 25 throw-off-key mechanism manually settable and automatically becoming locked in set position, to oppose release of the state-determining member, said throw-off-key mechanism arranged so as to be controlled by the general operator, thereby to 30 become unlocked and restored during a cycle of the general operator.

7. In a machine constructed according to claim 6, the throw-off-key mechanism being operative to also restore and then hold the state-determining member if the latter has been released. 35

8. In a computing machine having a set of computing pinions, indexable drivers therefor, and a reciprocating general operator for the drivers, the combination of a normally latched spring-driven state-controller for the computing pinions, said state-controller being selectively releasable before a cycle of the general operator to enable the latter, preparatory to the advance and return of the drivers, to respectively mesh 40 and unmesh the pinions and drivers, a restoring member for said state-controller, means whereby the general operator actuates said restoring member, including a hooked link connected to the restoring member, a spring-device urging said link into the path of the general operator so that its hook is picked up by the latter toward the end of its return stroke, means operative under control of the general operator as the latter reaches the end of its return stroke to cause said link to 45 become disengaged from the general operator, and a spring urging the disengaged link and hence said restoring member to a retracted position to clear the state-controller for subsequent setting. 50

9. The combination with a set of computing pinions, indexable drivers therefor, and a reciprocating general operator for the drivers, of a spring-driven state-controller selectively releasable before a general-operator cycle, to determine 60 co-operation of said pinions with their drivers during said cycle, a restoring bar for said controller, a rock-shaft having spaced arms connected to the restoring bar for moving the latter in parallelism transversely of itself, a draw-link 70 connected to said rock-shaft and having a hook normally in advance of a hook-engaging part of the general operator when the latter is in normal position, said link being arranged so that its hook is engaged by said general-operator part in the 75

- return stroke of the general operator, to thereby draw the link, means operative under control of the general operator whereby the hook becomes disengaged from the general operator when the link has been drawn far enough to restore the controllers by means of said bar, and a spring whereby, upon the disengagement of said hook, the restoring bar is restored to free the state-controller for subsequent setting.
10. In a computing machine having a carriage and a register normally in neutral condition and shiftable to be operative additively or subtractively, the combination of a spring-driven state-controller releasable, under control of the carriage, from neutral controlling position to additive or subtractive controlling position, a lever having one arm connected to said controller for restoring the same, a movably-mounted cam for engaging the other arm of said lever to operate the latter, said cam having a latching shoulder terminating its rise, and a throw-off key connected to operate said cam, said cam being advanced by said key, for the restoration of said state-controller, until said other lever-arm, under the influence of the state-controller-spring, drops behind said latching shoulder to thereby interlock with said cam and hold the state-controller in neutral position.
11. In a machine constructed according to claim 10, in which said cam is provided with a retracting spring effective upon withdrawal of said other lever-arm to restore said cam, said lever-arm withdrawal being effected by moving the state-controller, in restoring direction, slightly past its neutral position.
12. In a computing machine having a set of computing pinions, indexable drivers therefor, said pinions normally disengaged from said drivers, cycling mechanism for said drivers, and a carriage, the combination with means conditionable by said carriage in a computing zone, to determine engagement of said pinions and drivers when the cycling mechanism is operated, of throw-off-key mechanism settable to a latched position and operative, when set, to neutralize a carriage-controlled condition of said means pending a cycling operation, to thereby silence engagement of the computing pinions and drivers during said cycling operation, said throw-off-key mechanism being arranged to become automatically restored by means of said cycling mechanism during said cycling operation, thereby to restore subserviency of said carriage-conditionable means to said carriage.
13. In a computing machine having a set of computing pinions, indexable drivers therefor, said pinions normally disengaged from said drivers, a carriage, and cycling mechanism for the drivers, the combination with means normally disconnected from said cycling mechanism and operable by the latter for shifting said computing pinions into and out of engagement with said drivers, and means releasable by said carriage in a computing zone to immediately connect said pinion-shifting means to said cycling mechanism, and thereby automatically determine operation of said computing pinions during a cycling operation, of throw-off-key mechanism settable to a latched position to restore and retain said carriage-released means or to prevent movement of the latter to effective position, thereby to silence the carriage-determined operation of the computing pinions during a cycling operation, said throw-off-key mechanism being arranged to become automatically unlatched by means of said cycling mechanism, and thereby released for restoration, at an appropriate time in said cycling operation.
14. In a computing machine having a set of computing pinions, indexable drivers therefor, said pinions normally disengaged from said drivers, a carriage, and cycling mechanism for the drivers, the combination with means normally disconnected from said cycling mechanism and operable by the latter for shifting said computing pinions into and out of engagement with said drivers, means releasable by said carriage in a computing zone to immediately connect said pinion-shifting means to said cycling mechanism, and thereby automatically determine operation of said computing pinions during a cycling operation, of throw-off-key mechanism operable, before said carriage enters a computing zone, to interlock with said carriage-releasable means to prevent movement of the latter to effective position, said cycling mechanism being operable to disengage said interlocked throw-off-key mechanism and carriage-releasable means.
15. In a computing machine, the combination of a plurality of reciprocatory register-bars, each having depressible digit-pins, each bar having a pin-restoring member, a reciprocatory general operator for said bars, means actuatable for engaging and actuating said pin-restoring members in the return stroke of said bars to restore the depressed pins, a rock-shaft having means to engage and actuate the several pin-restoring-member-engaging means, a link connected to said rock-shaft and having a hook engageable by said general operator in its return stroke to draw said link and thereby rock said shaft, means controlled by said general operator and actuatable to automatically disengage said link at the end of said general operator return stroke, and a spring to restore said rock-shaft and link when said link is disengaged.
16. In a computing machine, the combination of a series of racks each having settable digit-pins, computing pinions operable by said racks, a reciprocatory general operator, a spring-pressed state-controller releasable to determine a computing state of said pinions, a member actuatable to restore said controller, mechanism for restoring said digit-pins, a link engageable by and carried along with said general operator toward the end of its return stroke, connections enabling said link when actuated by the general operator to actuate the pin-restoring mechanism and the restoring member for said controller, and means controlled by said general operator and actuatable for disengaging said link at the end of said stroke.
17. In a computing and printing machine having a paper-carriage, computing pinions, indexable drivers therefor, and a general operator for the drivers, said pinions normally disengaged from said drivers, the combination with means automatically brought into play by said carriage in a certain zone whereby the pinions and drivers are caused to be engaged during a subsequent cycle of the general operator, of a key, and means settable by said key to suppress said carriage-controlled means and thereby suppress the carriage-determined engagement of said pinions and drivers during said cycle, said key-set means arranged to become automatically restored by the general operator at an appropriate time in said cycle.
18. In a computing machine having computing pinions, indexable drivers therefor, and a general operator for the drivers, the combination with means automatically brought into play by said carriage in a certain zone whereby the pinions and drivers are caused to be engaged during a subsequent cycle of the general operator, of a key, and means settable by said key to suppress said carriage-controlled means and thereby suppress the carriage-determined engagement of said pinions and drivers during said cycle, said key-set means arranged to become automatically restored by the general operator at an appropriate time in said cycle.

- tion with state-controlling means differentially settable from a neutral position for predetermining additive or subtractive co-operation of said pinions and drivers during a subsequent 5 cycle of the general operator, a throw-off key, and means settable at will, before a cycle of the general operator, by said key for suppressing said state-controlling means, said key-set means arranged to become automatically restored by 10 said general operator at an appropriate time in said cycle.
19. In a computing machine having a register, a carriage, and a spring-pressed state-controller for said register normally in neutral position and 15 releasable by said carriage to predetermine addition or subtraction in said register, the combination of a lever for restoring said state-controller if it has been previously released, a throw-off key, and means connecting said key and lever whereby operation of said key actuates said lever to restore the released controller and latches the lever to hold the controller in neutral position, said lever-actuating means becoming releasably interlocked with said lever to 25 effect the latching of said lever.
20. In a computing machine having a register, a carriage, and a spring-pressed state-controller for said register normally in neutral position and releasable by said carriage to predetermine 30 addition or subtraction in said register, the combination of a lever for restoring said state-controller if it has been previously released, a throw-off key, means connecting said key and lever whereby operation of said key actuates said lever to restore the released controller and latches the lever to hold the state-controller in neutral position, said lever-actuating means becoming releasably interlocked with said lever to effect the latching of said lever, and cycling 35 mechanism arranged for restoring said state-controller subsequently to its release by the carriage, said cycling mechanism overthrowing the state-controller beyond said neutral position, the lever actuating and latching means being arranged to escape and effect the restoration of the throw-off-key mechanism when the cycling mechanism acts to overthrow the state-controller.
21. In a computing machine having a register, a carriage, and a spring-pressed state-controller for said register normally in neutral position and releasable by said carriage to predetermine addition or subtraction in said register, the combination of a lever for restoring said state-controller if it has been previously released, a throw-off-key, means connecting said key and lever whereby operation of said key actuates said lever to restore the released controller and latches the lever to hold the state-controller in neutral position, said lever-actuating means becoming releasably interlocked with said lever to effect the latching of said lever, and means operable to release the interlock of said lever and lever-actuating means and thereby cause restoration of the throw-off-key mechanism.
22. In a computing machine having a set of computing pinions, indexable drivers therefor, said pinions normally disengaged from said drivers, a carriage, and a general operator, the combination with means normally disconnected from the general operator, for shifting said set of pinions into engagement with said drivers, normally latched spring-pressed means releasable by said carriage for connecting said pinion-shifting means to said general operator, of throw-off-key mechanism settable, before the cycling operation, to a latched position to restore and retain the carriage-released connecting means, said throw-off-key mechanism being arranged so that when set it becomes automatically restored by means of the general operator during the cycle, said throw-off-key mechanism also being operative when set to prevent movement to effective position of the carriage-released means.
23. In a computing machine having a set of computing pinions, drivers therefor, said pinions and drivers normally disconnected, a carriage, indexing mechanism co-operating with said carriage for indexing said drivers, and a general operator for the drivers, the combination with means operable under control of said carriage, to effect engagement of the drivers and computing pinions during a cycle of said general operator, of throw-off-key mechanism, settable, and operative when set, to suppress said carriage-controlled pinion-engagement effecting means, said throw-off-key mechanism being effective irrespective of whether it is set before or after the indexing operation, and being also arranged to be restored, if set, by means of the general operator during the cycle.
24. In a computing machine having a set of reciprocatory register-bars having certain parts alternately engageable for reciprocating said bars; and having a general operator for the register-bars including a reciprocatory bar extending transversely of the register-bars for reciprocating the latter by engaging said parts, the combination with said transverse general-operator bar, of means to absorb the impact as said parts are engaged, including closely-wound helices forming the register-bar driving faces of said general-operator bar and extending lengthwise along opposite faces of said general-operator bar, a resilient backing between each helix and the general-operator bar, and a retaining rod extending through each helix, the ends of said retaining rod projecting beyond the ends of the helix, said rod-ends being secured to said general-operator bar to thereby retain said helix.
25. In a multiple-register computing machine having a plurality of parallel and laterally spaced sets of register-bars, each register-bar having digit-pins individually depressible; a pin-setting mechanism including, in combination, a key-operated rock-shaft for each digit, the several rock-shafts arranged in parallel array, said rock-shaft array extending transversely of the register-bars, and the array of register-bar sets extending laterally beyond the rock-shaft array, pin-setting linkage for each rock-shaft and extending across all the register-bars, each linkage including a cross-link, an arm on the rock-shaft engaging said cross-link for imparting endwise movement thereto, a second cross-link depressible edgewise for setting a digit-pin in any set of register-bars, bell-cranks disposed beyond the sides of the array of rock-shafts and linking said endwise movable cross-link and said depressible cross-link, fixed fulcrums for the bell-cranks of the several linkages, and an additional arm on each rock-shaft operative, when the rock-shaft, its first-mentioned arm, and the endwise movable cross-link co-operate to effect depression of the depressible cross-link, to follow up and bear on said depressible cross-link to support it against upward deflection when setting a pin, said first arm and said additional arm acting jointly on said pin-setting linkage.
26. In a multiple-register computing machine

having a plurality of parallel and laterally spaced sets of register-bars, each register-bar having digit-pins individually depressible; a pin-setting mechanism including, in combination, a key-operated rock-shaft for each digit, the several rock-shafts arranged in parallel array, said array extending transversely of the register-bars, and the array of register-bar sets extending laterally beyond the rock-shaft array, pin-setting linkage for each rock-shaft and extending across all the register-bars, said linkage including a cross-link, an arm on the rock-shaft engaging said cross-link for imparting endwise movement thereto, a second cross-link depressible edgewise for setting a digit-pin in any set of register-bars, bell-cranks disposed beyond the sides of the array of rock-shafts and linking said movable cross-link and said depressible cross-link, fixed fulcrums for the bell-cranks of the several linkages, and means connected to each rock-shaft and arranged to engage and support the depressible cross-link against upward deflection as said shaft, its said arm, and endwise movable link cooperate to set a pin, said arm and said depressible-cross-link engaging means acting jointly on said linkage.

27. In a computing machine having a set of totalizer-wheel-driving racks, each rack having settable digit-pins, and a general-operator bar extending transversely of the racks and reciprocatable for advancing the racks by means of the set digit-pins, the combination with said transverse general-operator bar, of a closely-wound helix extending along and abutting said general-operator bar, a keeper-rod extending through said helix and having its ends projecting beyond the ends of the helix and attached to said bar for retaining said helix adjacent to the rack-driving face of said bar, and individually movable fingers, one for each rack, mounted on said general-operator bar and backed by said helix, said fingers forming the means by which said general-operator bar engages the set digit-pins, and said helix acting to deaden the noises incident to the engagement of said pins by said fingers.

45. 28. In a computing machine having reciprocatory register-bars, each register-bar having settable index-pins and a shoulder, engageable respectively for advancing and returning the register-bar, and a general-operator bar extending transversely of the register-bars and reciprocatable for driving said register-bars by means of said pins and shoulders, the combination with said transverse general-operator bar, of means to absorb the impact as the register-bars are engaged, said means including closely-wound helixes forming the register-bar-driving faces of said general-operator bar and extending lengthwise along the opposite faces of said bar, a resilient backing between each spring and the general-operator bar, 69 and a keeper-rod extending through each spring, the ends of said rod projecting beyond the ends of the spring and being attached to said general-operator bar to retain said springs, said general-operator-bar faces each having a longitudinal slot in which the spring and backing are retained.

29. In a computing machine having a set of computing pinions, indexable drivers therefor, said pinions normally disengaged from said drivers, and a carriage, the combination with a cycling mechanism for the drivers, a device operable by the cycling mechanism, but normally disconnected therefrom, for shifting said pinions into engagement with said drivers, and means, releasable by said carriage in a computing zone and operative when released, to connect said

pinion-shifting device to said cycling mechanism preparatory to a cycling operation, of throw-off-key mechanism settable from an idle to an effective condition and arranged so that, by a setting thereof, said throw-off-key mechanism interlocks with said carriage-releasable connecting means to prevent operation of the latter, or, if said carriage-releasable connecting means be already released and operated, the setting of said throw-off-key mechanism restores, interlocks with, and thereby restrains said connecting means, said throw-off-key mechanism being settable before the cycling operation, and said cycling mechanism being operative to disengage said interlocked throw-off-key mechanism and carriage-releasable connecting means, and thereby effect restoration of said throw-off-key mechanism.

30. In a computing machine arranged to accommodate one or a plurality of sets of register-bars, the plurality of register-bar sets being laterally spaced across the machine, each register-bar having depressible digit-pins, a parallel motion pin-setting linkage for each digit, including a cross-bar long enough to span the plurality of register-bar sets and depressible to set a digit-pin of the same value in any register-bar of any set, a companion cross-bar, parallel motion connections at the ends of said cross-bar, whereby endwise movement of the companion cross-bar effects downward movement of the pin-setting cross-bar, said parallel motion connections being pivotally supported, said cross-bars being slender in proportion to their register-bar-spanning length, in order to minimize their inertia, and a digit-key-driven connection working upon said cross-bars at a location which is intermediate, laterally, of said cross-bar ends, said key-driven connection including an arm engaging said companion cross-bar to move the latter endwise, and a co-operating arm engaging the pin-setting cross-bar to concomitantly urge the latter downwardly and thereby act to support the slender pin-setting cross-bar against upward deflection at the pin-setting operation.

45. 31. In a multiple-register computing machine having a carriage, and having a cycling general operator for accumulating indexed amounts in selected registers, the combination with a set of individually conditionable state-controllers, one for each register, and permanently settable means enabling the carriage to automatically condition said state-controllers according to a predetermined program, of a set of sub-control keys, one for each register, selectively settable at will, means to enable any operated key to control the associated register independently, said key-operated means having individual means for automatically detenting them in effective positions, and cycle-operated means acting to cause restoration of said key-operated means and consequent automatic resumption of the original control of the state-controllers by said carriage.

32. In a computing machine having a carriage, a set of pre-indexable selectable registers for adding or subtracting, and a cycling general operator for running the pre-indexed amount into the selected registers, the combination with a set of state-controllers for said registers, each state-controller being differentially settable from a neutral normal position to select, and pre-determine additive or subtractive use of the corresponding register in the general-operator cycle, the state-controller normally determining non-use of said register, and primarily set-up means

enabling said carriage at its entry into a computing zone to select and cause differential setting of any one or more of the state-controllers, according to a pre-determined program, of a set 5 of selectively settable throw-off-key mechanisms, one for each register, each throw-off-key mechanism acting, when set, to counter the corresponding state-controller and thereby throw off use of the corresponding register as determined by the 10 carriage, said throw-off-key mechanisms having connections controlled by said general operator whereby any set throw-off-key mechanism is automatically restored during a cycle of the general operator, whereby an amount may be computed in one or more registers independently of 15 said program, and said program thereupon automatically becomes effective again.

33. In a multiple-register computing machine having a carriage, and having a general operator 20 to be cycled for accumulating indexed amounts in selected registers, the combination with permanently settable state-control means, for enabling the carriage automatically to control the states of individual registers according to a pre- 25 determined program, of preelimination mechanism selectively settable at will to neutralize the state-control temporarily in respect to any one or more registers, whereby, on occasion, an amount may be computed in one or more registers 30 independently of said state-control, and whereby the temporarily interrupted program may be thereupon resumed automatically, said preelimination mechanism including a set of preelimination devices, one for each register, selectively settable for temporarily controlling the 35 registers individually independently of said state-determining means, means for mechanically holding the selected pre-elimination devices in set operative positions, and cycle-operated means for automatically effecting resumption of the permanent control by said state-controlling means according to the original selective setting thereof.

34. In a computing machine of the character described provided with a carriage and having registers in each of which computing pinions are 45 shiftable from a neutral position to adding or subtracting position relative to indexable drivers for said pinions; the combination of a cycling general operator for the drivers, pinion-shifting means for each register, the several pinion-shifting 50 means being selectively conditionable before a cycle for enabling the general operator to shift the pinions additively or subtractively, according to a program, means acting automatically under control of said carriage to condition said pinion-shifting means for addition or subtraction, and a throw-off-key mechanism including a settable key 55

for every register, each key operating, when set, to prevent or suppress the automatic conditioning of its associated pinion-shifting means for a single cycle, independently of other keys and registers, to thereby, for said cycle, prevent or suppress the shift of the computing pinions for that register by the general operator, means being provided whereby the set throw-off key automatically becomes restored by the general operator at an appropriate period of the cycle. 10

35. In a computing machine provided with a carriage and having a plurality of registers, the combination of cycling mechanism for the registers, state-controllers, one for each register, means acting automatically under control of the 15 carriage, as the latter enters a computing zone, to condition said state-controllers according to a program, to predetermine additive or subtractive use of the respective registers, a throw-off-key mechanism, including a settable throw-off key 20 for each register, settable at will, preparatory to the cycling operation, to restore the carriage-conditioned controller for that register or to prevent it from being conditioned, independently of the other state-controllers and registers, for intermitting said program, and means causing the set throw-off key to be automatically restored by the cycling mechanism during the cycling operation, to render said program effective again. 25

36. In a multiple-register computing machine 30 having a carriage, the combination with a plurality of sets of computing pinions, indexable computing pinion drivers, said pinions and drivers being normally disconnected, and a general operator for cycling the drivers, of means, for 35 each set of computing pinions, conditionable to predetermine connection of that set of computing pinions and drivers for computing during a subsequent general-operator cycle, a state-controller for each set of computing pinions operable 40 to condition said means, means enabling the carriage at the several computing zones to co-operate with said state-controllers to condition said conditionable means according to a carriage-controlled program, a throw-off-key mechanism 45 including a settable throw-off key for each set of computing pinions, said key being settable at will before said cycle to suppress the associated state-controller and thereby, contrary to the carriage-controlled program, prevent connection of 50 that set of computing pinions and drivers independently of the other keys and sets of computing pinions, and means causing the set throw-off key to become automatically restored by the general operator at an appropriate time in the cycle, 55 for rendering said program effective again.

HENRY L. FITMAN.
